Attorney

UNITED STATES PATENT OFFICE.

JOHN W. JOHNSON, OF BESSEMER, MICHIGAN, ASSIGNOR OF ONE-HALF TO JAMES A. O'NEILL, OF IRONWOOD, MICHIGAN.

BUNDLE-CARRIER FOR GRAIN-BINDERS.

Specification of Letters Patent.

Patented Oct. 29, 1918.

1,283,203.

Application filed January 22, 1918. Serial No. 213,140.

To all whom it may concern:

Be it known that I, JOHN W. JOHNSON, a citizen of the United States, residing at Bessemer, in the county of Gogebic and State 5 of Michigan, have invented certain new and useful Improvements in Bundle-Carriers for Grain-Binders, of which the following is a specification.

This invention relates to new and useful 10 improvements in bundle carriers for grain binders.

The primary object of the invention is the provision of a retainer for bundles arranged as an attachment for the bundle carrier of a 15 grain binder and adapted for automatic adjustment during the delivery or discharge of the bundles from the carrier.

The further object of the invention is the provision of a device that is easy and inexpensive to manufacture and readily attached 20 to a binder for preventing bundles of grain from accidentally falling from the bundle carrier, the device being readily adjustable for attachment upon any form of grain 25 binder.

A still further object of the invention is the provision of a bundle carrier attachment for binders in the nature of a retainer for bundles normally positioned for maintaining the grain upon the carrier and readily swinging out of the way giving direction 30 to the discharge of the bundles when they are deposited upon the ground, the device thereafter automatically returning to its 35 normal operative position.

With these general objects in view and others that will appear as the nature of the invention is better understood, the same consists in the novel construction and arrangement of parts hereinafter fully described, 40 illustrated in the accompanying drawing and then claimed.

In the drawing forming a part of this application and in which like reference characters designate corresponding parts throughout the several views:

Figure 1 is a perspective view of the tines operatively arranged upon a binder in connection with the bundle carrier thereof, the 50 latter being indicated by dotted lines;

Fig. 2 is an elevational view of the adjacently positioned portions of the main members of which the device is constructed; and

Fig. 3 is an elevational view of the same assembled.

It being understood that the device comprises a grain retainer for bundle carriers of such agricultural implements as binders, the same is herein illustrated in connection with the bundle carrier 10 of a binder 11, the said 60 carrier having a plurality of tines 12 for supporting the sheaves of grain thereon, the carrier being dumped in the usual manner for discharging the bundles therefrom upon the ground during the rearward swinging 65 movement of said tines 12 in the direction indicated by the small arrows in Fig. 1 of the drawing.

A brace rod 13 is attached by means of an adjustable clamp 14 to a desirable portion 70 of the binder 11 such as the casting 15, spaced above the inclined board 9 down which the bundles travel to the carrier 10. The said rod has an open coil 16 at its free 75 end adapted for receiving a hub 17 there-through arranged upon the adjacent free end of a forked brace 18.

This brace 19 is formed of two rods 19 attached as at 20 to a suitable portion of the framework of the binder 11 with the outer 80 ends of the rods 19 welded together and provided cylindrical in form, constituting the hub 17 heretofore referred to. A stop-washer 21 is arranged at the inner end of the hub 17 against which the coil 16 is adapted to abut and whereby the braces 18 and 85 19 form a stable although resilient mount for a fender 22.

The fender 22 is substantially U-shaped, 90 being in the form of a fork having a relatively longer arm 23 and shorter arm 24 with a coil 25 provided therebetween, journaled upon the hub 17 when the device is assembled. The longer arm 23 has a curved tine 26 while the shorter arm 24 is arranged with a 95 forked tine 27 and being also of a general curvature of the tine 26.

A washer 28 is arranged upon the hub 17 outwardly of the fork coil 25 while a cotter 29 is secured through the said hub adjacent 100 the outer free end thereof, adapted for retaining the fork 22 journaled for oscillating thereon. The coil 16 of the rod 13 has an outwardly projecting angular finger 30 beneath the longer arm 23 of the fork 22, the said 105 longer arm being adapted to be maintained

- normally horizontally by resting of its own weight upon the finger 30. The longer arm 23 and its tine 26 are of greater weight than the forked tine 27 for normally maintaining the fork 22 with its arms 23 and 24 horizontal and with the pointed ends of the tines 26 and 27 arranged intermediate the tines 12 of the bundle carrier 10 and adjacent the outer free ends of said bundle carrier tines.
- 10 The operation of the device will be understood from this detailed description thereof, the fork 22 preventing the bundles from falling off of the outer free end of the carrier 10, while upon dumping the said carrier 15 by the operator of the binder, the forked portion or auxiliary fork 31 of the tine 27 will swing downwardly with the bundle as the bundle is deposited rearwardly upon the ground and during which operation the tine 20 26 will be eliminated. When the bundle has been delivered, the carrier 10 returns to its normal position while the fork 22 automatically swings to its normal position by reason of the weight of the longer arm 23 and 25 the fork is then positioned for retaining bundles of grain upon the carrier.
- By adjusting the clamp 14 upon the binder 11, the position of the fork 22 may be accurately arranged with respect to the carrier 30 10, and it will be seen that the device includes but a few elements which are inexpensive to manufacture and readily assembled together, as well as attached to a binder ready for use in connection with the bundle carrier thereof.

What I claim as new is:—

1. A device of the class described comprising in combination with the bundle carrier of a binder, brace rods mounted upon the binder and attached together at their outer ends, a retaining fork journaled upon said brace rods to tilt from its normal operative position upon the discharge of a bundle from the carrier and weighted to automatically return to its operative position after each actuation of the device.
2. An attachment for bundle carriers comprising a support having a hub and a stop finger, means for attaching said support to a binder and an overbalanced fork journaled

upon said hub and seating upon said finger when the device is operatively positioned adjacent the free end of the carrier.

3. In combination with a binder having a bundle carrier provided with tines, support rods carried by the binder with a hub at their free ends above the carrier and a fork journaled upon said hub adapted for tilting movement upon the discharge of a bundle from the carrier and with one side of the fork of greater weight than the other side thereof, whereby the fork is adapted to automatically return to its normal retaining position adjacent the carrier subsequent to each delivering operation of the carrier. 65

4. A bundle retainer comprising brace rods adapted for attachment to a binder and having their adjacent ends attached together forming a hub, means for attaching said rods to a binder, a washer at the inner end 70 of the hub, an upper brace rod having a coil surrounding said hub and terminating in an angular finger adjacent the hub, a bundle retaining fork provided with a coil journaled upon said hub and arranged with one end 75 longer and heavier than the other whereby the fork is adapted for normal positioning in upright arrangement with the longer portion thereof seated upon said finger.

5. A bundle retainer comprising brace rods adapted for attachment to a binder having their adjacent ends attached together forming a hub, means for attaching said rods to a binder, a washer at the inner end 80 of the hub, an upper brace rod having a coil 85 surrounding said hub and terminating in an angular finger adjacent the hub, a bundle retaining fork provided with a coil journaled upon said hub and arranged with one end longer and heavier than the other whereby 90 the fork is adapted for normal positioning in upright arrangement with the longer portion thereof seated upon said finger, the shorter end of the said fork being of forked arrangement, a washer upon said hub outwardly of the fork coil, and a retaining cotter secured to the hub adjacent the free end 95 of the hub outwardly of the said coils.

In testimony whereof I affix my signature.
JOHN W. JOHNSON.
